Milton C. Whitaker, Inventor
By his Attorney, Friedle Wright & Small

UNITED STATES PATENT OFFICE.

MILTON C. WHITAKER, OF BALTIMORE, MARYLAND, ASSIGNOR TO U. S. INDUSTRIAL
ALCOHOL CO., A CORPORATION OF WEST VIRGINIA.

CONTAINER FOR VOLATILE LIQUIDS.

1,400,193.

Specification of Letters Patent. Patented Dec. 13, 1921.

Application filed August 6, 1920. Serial No. 401,694.

To all whom it may concern:

Be it known that I, MILTON C. WHITAKER, a citizen of the United States, residing at Baltimore, State of Maryland, have invented 5 a certain new and useful Improvement in Containers for Volatile Liquids, of which the following is a specification.

My invention relates particularly to a container adapted to be used for discharging 10 when desired, small quantities of volatile liquids, but which is especially adapted to be used as a container for priming fluids used for starting internal combustion engines.

The object of my invention is to provide 15 a container of the above character which is so constructed as to be entirely vapor tight when prepared for sale and which may be readily opened for the discharge of the liquid, and again closed in a convenient manner, so as to make it substantially vapor 20 tight. A further object of my invention is to provide a container of this kind having a puncturable diaphragm, which, when punctured may be closed in such a way as to prevent 25 the escape of the vapors of the volatile fluid. In previous constructions the puncturable diaphragms have been provided with circular ridges surrounding the areas to be punctured and disk valves have been brought 30 into contact with the ridge to prevent the outward flow of the liquid when closed. Inasmuch, however, as in such a diaphragm the area to be punctured is comparatively 35 large, and the surrounding ridge is of considerable length, there is a comparatively long distance to be closed by the valve and a correspondingly great opportunity for the escape of the contents. For this reason a volatile and comparatively expensive liquid 40 could not be used in such containers. Furthermore, in the previous constructions it was customary to locate the closing valve at one part of the closure in the opening giving access for puncturing the diaphragm and 45 a discharge spout at another portion of the closure. By means of my invention, on the other hand, the escape of vapors and loss of liquid through the puncture in the diaphragm is prevented by closing a comparatively minute aperture in the apparatus and the same opening in the closure which gives 50 access to the diaphragm for the puncture

contains both the discharge spout and the aperture-closing means.

Further objects of my invention will appear from the detailed description thereof contained hereinafter.

While my invention is capable of embodiment in many different forms, for the purpose of illustration I have shown only one 60 form of the same in the accompanying drawings, in which;

Figure 1 is a side elevation of a container made in accordance with my invention.

Fig. 2 is a vertical section of the same, and

Fig. 3 is a vertical section of a modified 65 form of container made in accordance with my invention.

In the drawings, referring to Figs. 1 and 2, I have shown a container of oval cross-section made of sheet metal of any desired character, as for example, tin, iron, nickel, brass, etc., comprising a main outer wall 1 having a bottom 2 and a top 3 crimped over the edge of said wall. The top 3 has a central 70 opening 4 on the edge of which there is soldered a puncturable diaphragm 5, crimped over a convex member 6 having an inwardly directed cylindrical portion 7 carrying a screw-thread. The screw-threaded portion 7 is provided for receiving a screw-threaded 75 cap 8 having a washer 9 therein to contact with the top of the convex member 6. The cap 8 is also interiorly screw-threaded to receive a cylinder 10 having a cork washer 80 11 at its upper end on the interior thereof retained in place by a ridge 12. The washer 11 contacts with the upper end of a discharge spout 13, the lower end of which is secured in any desired manner to the lower 85 inner edge of the cap 8.

The modification of my invention shown in Fig. 3, is constructed the same as the form of my invention previously described, except in the following respects: In this instance, 90 there is a top 14 having an annular groove or recess 15 surrounding an opening 15^a, in which there is soldered a convex member 16 having an inwardly projecting cylindrical portion 17, the lower portion of which forms 100 a puncturable diaphragm 17^a, which is screw-threaded to receive a cap 18 having an upper flange 18^a overlying a gasket 18^b, and a spout 19 attached to the lower end of the

same, so as to leave a screw-threaded recess 20 to which a cylindrical cover 21 is secured. Said cover 21 has a cork washer 22 fitting over the end of the spout 19, and there is an 5 inwardly directed ridge 23 to retain the washer in place.

In the operation of my invention, referring to Figs. 1 and 2, the container will be filled with any suitable volatile liquid, as for 10 example, a priming fluid which may be ether, acetone, or any other similar material or composition through the opening 4, after which the remaining parts are connected to the container by soldering the diaphragm 5 to the top 3 along the edge of the opening 4. The container is now ready for shipment and sale on the market. When the contents are 15 to be used, the cap 8, with its attached parts, is unscrewed, and the diaphragm 5 is punctured with a sharp instrument of any kind, after which the cap 8 is again screwed into 20 place and the cylinder 10 is unscrewed, thus disengaging the washer 11 from the end of the spout 13 and permitting the contents to 25 be discharged, as for example, into the pet-cocks of an internal combustion engine, by 30 pressing slightly upon the sides of the container. When the desired quantity of liquid has been discharged in this way, the container 35 is again closed by screwing the cylinder 10 into place, thus bringing the small discharge aperture of the spout 13 again into contact with the washer 11 and preventing the escape of the volatile vapors of the priming fluid. Where the fluid is of a very volatile 40 character and also comparatively expensive, it is necessary to prevent the rapid losses which would occur if the container should permit the escape of vapors of the same therefrom.

The modification of my invention shown in Fig. 3, operates the same as the modification 45 previously described, except that in this instance, the puncturable diaphragm 17^a is located on the convex member 16. This construction has the advantage of omitting one of the parts present in the preceding construction, and brings the puncturable diaphragm up to a more accessible position.

50 While I have described my invention above in detail, I wish it to be understood that many changes may be made therein without departing from the spirit thereof.

I claim:

55 1. A container for volatile liquids having a puncturable diaphragm, an opening giving access to said diaphragm and a nozzle carried in said opening.

60 2. A container for volatile liquids having a puncturable diaphragm, an opening giving access to said diaphragm and a nozzle screw-threaded in said opening.

65 3. A container for volatile liquids having a puncturable diaphragm, an opening giving access to said diaphragm, a nozzle car-

ried in said opening, and a cover closing the end of the nozzle.

4. A container for volatile liquids having a puncturable diaphragm, an opening giving access to said diaphragm, a nozzle screw-threaded in said opening, and a cover closing 70 the end of the nozzle.

5. A container for volatile liquids having a puncturable diaphragm, an opening giving access to said diaphragm, a nozzle carried in 75 said opening, and a cover closing the end of the nozzle and received in said opening.

6. A container for volatile liquids having a puncturable diaphragm, an opening giving access to said diaphragm, a nozzle screw-threaded in said opening, and a cover closing 80 the end of the nozzle and received in said opening.

7. A container for volatile liquids having a puncturable diaphragm, an opening giving 85 access to said diaphragm, a nozzle carried in said opening, and a cover closing the end of the nozzle and received in said opening by being screw-threaded to the nozzle portion located in said opening. 90

8. A container for volatile liquids having a puncturable diaphragm, an opening giving access to said diaphragm, a nozzle screw-threaded in said opening, and a cover closing 95 the end of the nozzle and received in said opening by being screw-threaded to the nozzle portion located in said opening.

9. A container for volatile liquids having a puncturable diaphragm, an opening giving access to said diaphragm, a nozzle carried 100 in said opening, and a cover having a washer closing the end of the nozzle.

10. A container for volatile liquids having a puncturable diaphragm, an opening giving 105 access to said diaphragm, a nozzle screw-threaded in said opening, and a cover having a washer closing the end of the nozzle.

11. A container for volatile liquids having a puncturable diaphragm, an opening giving access to said diaphragm, a nozzle carried 110 in said opening, and a cover having a washer closing the end of the nozzle and received in said opening.

12. A container for volatile liquids having a puncturable diaphragm, an opening giving 115 access to said diaphragm, a nozzle screw-threaded in said opening, and a cover having a washer closing the end of the nozzle and received in said opening.

13. A container for volatile liquids having 120 a puncturable diaphragm, an opening giving access to said diaphragm, a nozzle carried in said opening, and a cover having a washer closing the end of the nozzle and received in said opening by being screw-threaded to the nozzle portion located in said opening. 125

14. A container for volatile liquids having a puncturable diaphragm, an opening giving access to said diaphragm, a nozzle screw- 130

threaded in said opening, and a cover having a washer closing the end of the nozzle and received in said opening by being screw-threaded to the nozzle portion located in said opening.

15. A container for volatile liquids having a puncturable diaphragm, a nozzle adapted to discharge the liquid passing

through said diaphragm and a closure for the end of the nozzle screw-threaded to the base of the nozzle.

In testimony that I claim the foregoing, I have hereunto set my hand this 26th day of May, 1920.

MILTON C. WHITAKER.
